UNITED STATES PATENT OFFICE.

JAMES C. POTTER, OF PAWTUCKET, RHODE ISLAND.

SPINNING MACHINE.

Application filed December 5, 1921. Serial No. 520,078.

To all whom it may concern:

Be it known that I, JAMES C. POTTER, residing at Pawtucket, county of Providence, and State of Rhode Island, a citizen of the 5 United States, have invented certain new and useful Improvements in Spinning Machines, of which the following is a specification.

The builder motion as now used in spinning machines includes a cam, the employment of which is objectionable for various reasons. It requires heavy weights to move the builder arm or lever in opposition to the cam. The motion from the cam is not 10 always smooth and easy but may be jerky and thus result in improperly formed cops. One object of my invention is to provide a builder motion which will be free from the just-noted objections. Another object of 15 my invention is to provide a builder motion whose lever or arm will move with great power. Other objects and advantages of my invention will be understood and appreciated by those skilled in the art when the embodiment of such invention illustrated in the 20 drawings is explained, some of which are pointed out hereinafter. My invention consists in what is described by or is embraced within the meaning or scope of the appended 25 claims.

The embodiment of my invention appearing in the drawings is a ring-spinning machine in which the ring rails are stationary and the spindles are traversed, and such machine is a type invented by me in which the builder motion is located at midlength of the machine, but it is to be understood that my invention is not limited to machines in which the ring-rails are stationary and the spindles 30 traverse but extends to machines in which the ring-rails are the traversing members, nor is my invention limited to application to a machine in which the builder motion is at midlength, for it may be embodied when the 35 builder motion is at one end and it may be embodied in machines in which the ring-rails are traversed and the builder motion is located at midlength of the machine.

In the drawings:

50 Fig. 1 is a view partly in elevation and partly in section from front to back of the machine of the spinning machine shown to exemplify one embodiment of my invention;

Fig. 2 is a front elevation of the middle 55 portion of such machine;

Fig. 3 is a horizontal section on the line 3—3 of Fig. 1;

Fig. 4 is a horizontal section on the line 60 4—4 of Fig. 1;

Fig. 5 is a section on line 5—5 of Fig. 2;

Fig. 6 is a detail view in perspective of some of the separators.

In its general construction, the machine shown in the drawings is similar to that of 65 the machine of my United States Patent No. 1,401,729, issued December 27/21, it having at midlength of the machine two heads, 10, spaced apart and between which are mounted the driving mechanism for the tin 70 rollers of the two sections of the machine and the builder motion, the driving mechanism comprising a belt, 11, which passes over pulleys, 12, which are mounted upon and partake of vertical movement of the 75 carriages, 13, upon which the spindles, 14, are mounted for their traversing movement through their rings, 15, mounted on stationary ring-rails, 16, the threads of yarn being delivered by front feed or draw rollers 80 to travelers, 17, on the rings.

The builder lever or arm, 18, is pivoted or hung at its upper end in a bracket, 19, which is bolted to the underside of a horizontal plate, 20, supported by the two heads, 85 10, and at its lower end it has a gear segment, 21, with which meshes a driving pinion, 22, which, as hereinafter explained, may be revolved in either direction and thereby the swinging or vibratory movement 90 of the builder arm, 18, is produced.

The pinion, 22, is on a short shaft, 23, to which is fixed a worm wheel, 24, that is driven by a worm, 25, on a horizontal shaft, 26. On the latter are pinned two oppositely 95 facing clutch collars, 27 and 28 respectively, and loose on the shaft, 26, between said collars is a slidable sleeve, 29, that has fixed to it two spur gears, 30 and 31, of different diameter, each having a clutch face so that alternately said gears may be engaged with the clutch collars, and thus the worm shaft 100 be driven by one gear or the other and at different speeds. Meshing with the larger gear, 30, is a gear, 32, fixed to a shaft, 33, 105 and also on the shaft, 33, is a smaller gear, 34, which by an idler gear, 35, is geared to the smaller gear, 31, and thus, as the shaft,

33, always rotates in the same direction, the worm shaft may be revolved alternately in opposite directions and thereby the builder arm or lever be positively but easily swung to and fro and with a smooth or steady, and powerful motion. The shaft, 33, is mounted in bearings in a frame, 36, and at one end has a bevel pinion, 37, which meshes with and receives motion from a bevel pinion, 38, on a shaft, 39, that has a sprocket wheel, 40, which by gearing that includes a sprocket chain, 41, is driven from one or the other pulleys, 12, as in the machine of my patent above mentioned.

15 The clutch sleeve, 29, is engaged by a lug, 42, on a yoke, 43, whose arms, 44, are pinned to a rod, 45, slidably mounted in the frame, 36. Upon the rod, 45, are two coiled springs, 46, which respectively bear at their outer ends against the yoke arms, 44, and between the springs, 46, is a finger, 47, that is attached to a rod, 48, slidably mounted in the frame, 36, so that it may move to and fro. When the rod, 48, moves in one direction it acts to compress one spring against one yoke arm and when moved in the opposite direction it acts to compress the other spring against the other yoke arm, the arm against which the spring is pushed being held by a latch, 49, against movement until the latch is released, whereupon the spring being free to act it will quickly move the yoke longitudinally and thereby shift the clutch sleeve, 29, to change the gear connection with the worm shaft. The latch, 49, has a shoulder, 50, which drops back of the yoke arm, 44, with which it coacts, and its free end has a bevelled nose, 51, against which the finger, 47, acts and after a certain amount of movement of the finger, the latch is cammed out of engagement with the yoke arm. The movement of the spring-compressing and latch-releasing finger, 47, is automatically produced by means of motion obtained from the builder motion arm which means comprises a pair of spaced lugs connected with such arm to partake of its motion and an extension, 52, of the finger, 47, which is situated between said lugs and is engaged by one or the other according to the direction of movement of the builder motion arm or lever. Said lugs may be carried by a rod pivotally connected at one end to the builder motion arm or lever, 18, but for reasons that will presently appear, I prefer the construction illustrated in the drawings. In the drawings, said lugs, 53, are each carried by a nut, 54, upon a shaft, 55, that has right and left hand threads to engage the respective nuts so that by its revolution in one direction the nuts will be moved towards one another and by its rotation in the opposite direction, they will be moved away from each other. The shaft, 55, is mounted in bearings in a tubular or hollow rod, 56,

which at one end has a lateral extension, 57, which has a sleeve, 58, through which passes a shaft, 59, supported by the builder motion arm or lever, 18. Upon the shaft, 55, is a bevel pinion, 60, which meshes with a bevel pinion, 61, loose on the shaft, 59, and attached to the hub of said bevel pinion, 61, is a ratchet wheel, 62, with which coacts a pawl, 63, on an arm, 64, pivoted to the hub of the pinion, 61, so that by the oscillation of the arm, 64, the ratchet wheel may be turned intermittently and thereby the shaft, 55, revolved and the movement of the nuts, 54, and the lugs, 53, towards one another and towards the finger extension, 52, may be produced, this action being automatically produced when it is desired to wind the cops for warp thread. At other times for forming a different cop, the lugs, 53, are set at the desired adjustment so that at the proper time they will alternately engage the finger extension, 52, to cause the shifting of the clutch sleeve to reverse the direction of movement of the builder arm or lever, the tubular rod, 56, in such case being simply moved to and fro with the builder arm through its pivotal connection with the latter. The lugs, 53, project through a slot, 560, in the tubular rod, 56, and they and the finger extension, 52, are guided by a rod, 561, which passes through holes in them and which at opposite ends is supported by lugs, 562, which project from the tubular rod, 56. When the automatic movement of the nuts, 54, and the lugs, 53, for warp winding is to be effected a rod, 65, which at one end is pivoted to a bracket, 66, attached stationarily to one of the heads, 10, is pivotally connected to an eye, 67, as shown in dotted lines in Fig. 1. Upon the rod, 65, are two spaced apart collars, 68, which alternately, according to the direction of swing of the builder arm, engage a collar, 69, through which the rod, 65, slides and is attached to the arm, 64, by the eye, 67, and thus the to and fro movement of the arm, 64, effected. The number of teeth through which the ratchet wheel is turned depends upon the adjustment of the collars on the rod, 65. The rod, 65, may also, as shown in full lines in Fig. 1, be used to vibrate an arm, 70, which carries a pawl, 71, that coacts with a ratchet wheel, 72, to rotate a bevel pinion, 73, attached to the ratchet wheel, which pinion meshes with a bevel pinion, 74, on a shaft 75, which is journaled in bearings, 76, on the side of the builder motion arm, 18. On the shaft, 75, is a worm 77, which meshes with a worm wheel, 78, mounted on a stud shaft, 79, secured to the builder motion arm, and connected with the worm wheel, 78, is a pinion, 80, which meshes with a spur gear, 81, on a stud shaft, 82, on the builder motion arm, which gear 81, meshes with a similar gear, 83, on a stud shaft, 84, on the builder mo-

tion arm so that both gears 81 and 83 rotate simultaneously but in opposite directions. Fixed to the gear, 81, is a sprocket wheel, 85, and fixed to the gear, 83, is a sprocket wheel, 86, and to each sprocket wheel is attached one end of a sprocket chain, 87, whose other end is attached to a sprocket wheel, 88, with which is connected a sprocket wheel, 89, to which one end of a sprocket chain, 90, is attached whose other end is attached to a sprocket wheel, 91, on a shaft, 92, upon which are fixed pinions, 93, that mesh with racks, 94, that are connected with spindle carriages, 13. Through the sprocket chain connections I have described, the builder motion arm effects the vertical movement of the spindle carriages and by the pawl and ratchet mechanism acting through the shaft, 75, the sprocket chains, 87, are partially unwound from the sprocket wheels upon the stud shafts, 82 and 84, carried by the builder motion arm and thus the relative vertical position of the bobbins and the rings is changed as the winding of the cop proceeds. Of course, no turning of the sprocket wheels on the stud shafts, 82 and 84, occurs from the mere vibration of the builder motion arm and hence the vibration of such arm by pulling on the sprocket chains, 87, first in one direction and then in the other effects turning of the shaft, 92, by which the transverse of the spindle carriages is effected.

It will be seen that the matter of changing from one kind of winding to another involves merely changing the connection of the rod, 65, from one ratchet-wheel arm to another. Indeed, if desired, the machine may be provided with two rods, 65, one connected with one ratchet arm, 64, and the other with the other ratchet arm, 70, the one not to be active being left loose, and under some conditions of cop winding both may be simultaneously used. With the cam type builder motion, when a change is to be made, say from filling to warp, one cam must be substituted for another, the chain connections must be altered, and the usual quadrant which moves for filling must be secured in a stationary position.

An important feature of my invention is the long, powerful leverage which I obtain from the builder motion from my manner of mounting the builder motion arm or lever and the place of application of power thereto and the point of connection therewith of the chain device by which motion is imparted to the traversing member of the machine.

I do not confine myself to the use of separators to prevent ballooning and when separators are used I do not limit myself to any particular kind thereof, but when separators are used I prefer the construction shown in the drawings, each being in the form of a

tube, 95, that surrounds the bobbin on the spindle. To enable the thread to be passed into the tube and yet prevented from accidentally escaping therefrom, an obliquely extending slit, 96, may be provided or the slit may be parallel with the axis of the spindle but having the edges lap past one another. The separator being of metal with more or less elasticity, the slit permits it normally to expand and thus by friction the separator is held in the opening, 97, in a supporting plate, 98, by which it is pivotally attached to the vertical flange of the ring-rail, such pivotal attachment enabling the separator to be swung out of the way for convenience in doffing when the spindle is in its lowermost position. As a matter of convenient construction a number of separators may be supported by the same plate, 98. The separators are supported a substantial distance above the rings to allow access to the travelers in piecing broken ends and to encompass the ballooning threads at their greatest throw. They also constitute shields or guards that protect the threads from drafts of air that blow them about.

When my invention is embodied in a machine in which the spindles are movably supported so as to traverse through the rings, the spindles are mounted in a frame which comprises parallel front and back rails, 99, which rest loose upon bolts, 100, that pass through horizontal lugs, 101, on the vertically reciprocating slides so that said frame rails are not attached or fixed to the slide and hence should there be any want of parallelism of the slides due to improper setting of head and foot pieces and samsons or warping of the latter or should the floor on which the machine rests settle unequally, the loosely supported frame will be free to adjust itself to the conditions of its support.

What I claim is:

1. A builder motion for spinning machines comprising a to and fro movable member, an operative connection between the latter and the movable spinning element support, alternately acting power means, an operative connection between the latter and said member, and means for changing the direction of action of said power means controlled by said member.

2. A builder motion for spinning machines comprising a to and fro movable member, an operative connection between the latter and the movable spinning element support, two oppositely acting trains of gears, and means for alternately connecting them with said member, comprising a clutch under the control of said member.

3. A builder motion for spinning machines comprising a lever, an operative connection between the lever and the movable

- spinning-element support, alternately acting power means, an operative connection between the latter and said lever, and means for changing the direction of action of said power means connected with and receiving motion from said lever.
4. A builder motion for spinning machines comprising a lever, an operative connection between the lever and the movable spinning-element support, two oppositely acting trains of gears, and means for alternately connecting them with said lever comprising a clutch and clutch shifting means controlled by said lever.
- 10 5. A builder motion for spinning machines comprising a to and fro movable member, an operative connection between the latter and the movable spinning-element support, two oppositely acting trains of gears, means for alternately connecting them with said member, comprising a clutch, oppositely acting springs, and means for alternately placing the springs under compression and releasing them.
- 20 6. A builder motion for spinning machines comprising a to and fro movable member, an operative connection between the latter and the movable spinning-element support, and a plurality of separately acting means for controlling the movement of said support in conformity with the requirements of the particular cop being built mounted on and moving with such member, and stationarily supported means coacting therewith.
- 30 7. A builder motion for spinning machines comprising a to and fro movable member, an operative connection between the latter and the movable spinning-element support, means connected with and deriving motion from said member for controlling the movement of said support, and other means connected with and deriving motion from said member for controlling the movement of said support whereby the building of the cop may be controlled and stationarily supported means connectible at will with either of said means.
- 40 8. A builder motion for spinning machines comprising a to and fro movable member, an operative connection between the latter and the movable spinning element support, and alternately useable means for controlling the movement of said support to wind either warp wind bobbins or filling wind bobbins mounted on and moving with

such member, and stationarily supported means coacting therewith.

9. A builder motion for spinning machines comprising a to and fro movable member, an operative connection between the latter and the movable spinning-element support, means connected with and deriving motion from said member for controlling the movement of said support, and other means connected with and deriving motion from said member for controlling the movement of said support whereby the building of the cop may be controlled, each of said means comprising a pawl and ratchet device.

10. A builder motion for spinning machines comprising a to and fro movable member, an operative connection between the latter and the movable spinning-element support, alternately acting power means, an operative connection between the latter and said member that control the action of said alternately acting power means, and automatic means for varying the time of action of said alternately acting power means deriving motion from said member.

11. A builder motion for spinning machines comprising a to and fro movable member, an operative connection between the latter and the movable spinning-element support, alternately acting power means, an operative connection between the latter and said member, automatic means for varying the time of action of said alternately acting power means, comprising a clutch, two oppositely traveling devices adapted to act alternately on said clutch, and means deriving movement from the movement of said member to actuate said devices.

12. In a ring-spinning or twisting machine, the combination of rings and travelers thereon, a stationary support for such rings, thread feeding means situated a fixed distance from the ring, spindles, spindle rotating means, a carriage that supports the spindles, a builder motion for traversing said carriage and causing movement of spindles and bobbins supported thereby to and fro through the rings, the travelers deriving their motion only from the pull of the threads as the latter are wound upon the bobbins, and tubular separators supported a substantial distance from the rings.

In testimony whereof I hereunto affix my signature.

JAMES C. POTTER.
